JESSE W. DAVIS, OF WENATCHEE, WASHINGTON

LABELING MACHINE

Application filed January 7, 1929. Serial No. 330,797.

The present invention relates to labeling machines and the primary object of the invention is to provide a machine for automatically applying labels to packages or receptacles in a neat, quick and efficient manner without requiring manual handling of the packages or containers during the labeling operation.

A further object of the invention is to provide a labeling machine of such construction that the packages are fed thru the machine in such an angular position as to facilitate proper and effective applying and sealing of the labels to the packages.

A further object of the invention is to provide a labeling machine embodying novelly operating paste applying, label applying, and label affixing mechanisms which successively and automatically act upon the receptacles as moved with an intermittent movement thru the machine.

A still further and important object of the invention resides in the novel construction of the label applying gun.

Other objects and advantages of the invention will be apparent during the course of the following detailed description, taken in connection with the accompanying drawings forming a part of this specification and in which drawings:

Figure 1 is a top plan view of the machine and showing in dotted lines, the manner in which the packages or receptacles to be labeled are carried thru the machine.

Figure 2 is a side elevation of the machine and showing fragmentary portions broken away for illustrating details of construction.

Figure 3 is an end elevation of the machine at the feed end thereof.

Figure 4 is a vertical section taken substantially on the line 4-4 of Figure 1.

Figure 5 is an enlarged section thru the label gun taken on line 5-5 of Figure 2.

Figure 6 is an enlarged fragmentary section thru the label sealing means, on line 6-6 of Figure 2.

Figure 7 is an enlarged fragmentary detail section of the compensating means for the label gun for maintaining substantially an even pressure on the labels between throws of

the gun and when more or less labels are in the gun.

Figure 8 is an enlarged face plan view of the label sealing head.

Figure 9 is a fragmentary detail section thru the label sealing head for use when applying labels to containers made of wood or other relatively thick walls.

Figure 10 is a fragmentary detail section thru the label sealing head and showing a plain rim for use when sealing labels upon containers made of thin pasteboard, tin, etc.

Figure 11 is a fragmentary detail section thru the forward end of the label holder and showing the manner of retaining the labels against dropping from the open end of the holder.

Referring to the drawings in detail, and wherein similar reference characters designate corresponding parts thruout the several views, the letter A designates a conveyor rack upon which the receptacles or containers to have labels affixed thereto are supported during the labeling operation. The letter B may designate a mounting table or frame arranged along one side of the rack A for supporting the paste applicator C, label gun D, label sealing means E, said apparatuses C, D, and E being related in the respective order given from the feed to the discharge end of the conveyor rack. The letter F may designate a feed transfer for transferring the receptacles or packages from the feed conveyor G, and H the discharge transfer for removing the labeled packages from the conveyor rack 85 to a position upon the receiving conveyor or rack J.

The conveyor rack A for receiving and supporting the packages in positions to have labels affixed to one end thereof, includes a supporting frame embodying a pair of front and rear supporting rails 5 and 6 respectively provided with rollers 7 permitting free and easy movement of the packages along the supporting rails. These supporting rails 5 and 6 as will be observed in Figures 3 and 4 are arranged with the rear supporting rail 6 at a higher elevation than the front supporting rail 5 and with the axes of the rollers of the respective rails axially aligning. The

rails 5 and 6 may be mounted upon the upper ends of suitable uprights 8 arranged at suitably spaced points along the rails. At the forward ends of the rails 5 and 6, the rails extend downwardly as shown in Figure 2 to a position at one side of the feed conveyor G so that the packages when positioned on the conveyor rack by the feed transfer F may easily rise into position upon the transversely inclined runway formed by the supporting rails 5 and 6. Supported also upon the upper ends of the uprights or standards 8, are front and rear guide rails 9 and 10 respectively provided throughout their length with anti-friction rollers 11 adapted to engage opposite ends of the package or container and prevent movement thereof transversely across the supporting rails 5 and 6. As will be observed in Figures 3 and 4 the package or container P moves thru the conveyor rack or inclined runway in an angular position to the horizontal with the package having a normal tendency to move into engagement with the rollers of the front guide rail 9. The guide rails 9 and 10 are of course arranged at angles above the supporting rails 5 and 6 and by observing Figures 3 and 4 it will be seen that the rollers of the rear guide rail engage substantially at the medial height of the package while the rollers of the front guide rail engage the front end of the package at a position relatively near the top edge thereof so as to not interfere with and allow for labels of a size substantially equal to the end dimensions of the package to be affixed to the end of the package. That end of the front guide rail 9 at the feed end of the conveyor rack is extended downwardly and across the forward end of the feed conveyor G whereby the packages when moved down the preferably inclined feed conveyor G engage the downturned end of the guide rail and are stopped at a position to be elevated upon the conveyor rack by the feed transfer F. At the delivery end of the conveyor rack the rollers 7 are eliminated from the supporting rails 5 and 6 and the rails are slightly upwardly offset to provide slides 12 having their upper edges extending substantially flush with the upper edges of the rollers 7. These slides 12 are intended to receive and support the packages at the delivery end of the conveyor rack after the labels have been affixed to the packages. Since the slides 12 are at unequal elevations it is preferred that the front guide rail 9 be extended as shown in Figures 1 and 2 for preventing the package from sliding transversely off the slides due to the angular position of the package upon the slides. The packages after having the labels affixed thereto are moved upon the slides 12 from which they are lifted by the discharge transfer H to a position upon the receiving conveyor or rack J.

65 The mounting table or frame B which is

arranged along the front sides of the machine aside from serving as a support for the devices C, D and E also serves as a mounting for the gearing for driving the feed and discharge transfers F and H respectively. The intermediate portion of the table B is provided with an inclined portion B' which is inclined at an angle corresponding to the angle at which the packages pass thru the conveyor rack, and upon the inclined portion B' is mounted the label gun D and label sealing means E.

70 Mounted horizontally along the forward edge of the table B as in suitable bearings 13 is a main drive shaft 14 one end of which extends into a suitable gear case 15 containing suitable speed reducing gearing driven by a source of power such as an electric motor 16.

75 Referring now to revolving feed transfer F for transferring the packages to be labeled 80 from the feed conveyor G to a position upon the conveyor rack A, the same preferably consists of a pair of transfer arms 17 mounted adjacent one end upon a rotating shaft 18 extending transversely beneath the supporting rails 5 and 6 and preferably inclined at an angle corresponding to the inclination of the feed conveyor G. A counter-balancing weight 19 is preferably connected between the shorter ends of the arms 17, and the shaft 18 is so mounted with respect to the feed conveyor G that upon rotation of the shaft in the direction of the arrow shown in Figure 2, the longer ends of the arms will move upwardly thru the openings 20 provided in the feed conveyor and engage beneath the package for elevating the same into position upon the conveyor rack.

85 As the transfer continues rotation, the arms 17 carry the package past the paste applicator C for a distance as shown by the dotted position of the package P¹ in Figure 1. The transfer shaft 18 is preferably rotated continuously in one direction by means of a bevel gear 21 meshing with a bevel gear 22 mounted upon the forward end of the main drive shaft 14.

90 Arranged in the path of movement of the packages by the feed transfer F, is a pivoted keeper unit 23 embodying a counter-balanced roller 24 which is depressed when the package is moved over the keeper unit, and when the package has reached its limit of movement by the transfer, the counter-balanced roller is raised to its normal position and bears against the package for preventing return movement thereof along the conveyor rack. Limited rearward swinging of the unit 23 is obtained by means of a suitable cross bar or stop 24' carried by the support 100 105 110 115 120 125 130 135 140 145 150 155 160 165 170 175 180 185 190 195 suitable adhesive to the ends of the packages upon which the label is to be affixed, is arranged slightly rearwardly of the feed transfer drive shaft 18 and at a location whereby the feed transfer moves the packages past the applicator as the adhesive is being applied to the package. The paste applicator preferably embodies a substantially frusto-conical paste roll 26 adapted to be revolved by a shaft 27 suitably geared as at 28 to the main drive shaft 14. The paste roll 26 is intended to dip into a paste box or receptacle 29 supported upon the table B. By forming the roll 26 of frusto-conical formation such provides a relatively large paste applying surface without any appreciable thickness to the roll. The roll 26 is mounted on the shaft 27 by means of flexible tubular couplings 30 and which as will be apparent in Figure 4 will permit slight lateral tilting of the roll so that the conical face thereof will have proper contact with the end of the package and apply an even coating of adhesive thereover without requiring that the end of the package be perfectly flat and in right angular relation to the sides of the package.

The label gun D for applying labels to the paste coated ends of the packages is mounted in an inclined position upon the forward portion of the inclined table portion B' and includes a holder 32 in which is arranged a stack of labels 33 to be applied to the packages. The holder 32 is mounted for sliding movement in a suitable guide plate 34 provided with upstanding guide bearings 35 and 35'. As will be observed in Figure 5 the holder 32 is slidable toward and away from the paste coated end of the package P beneath the front guide rail 9 of the rack A. Fitting within the holder 32 is a follower plate 36 which bears against the stack of labels and acting upon the rear side of the plate 36 are suitable leaf springs 37 preferably secured to the rear wall of the holder and these springs act to normally urge the stack of labels forwardly in the holder. While the angular inclined position of the holder will prevent the front label from falling from the holder it is preferred that a slightly turned edge as at 38 in Figure 11 be provided for preventing possibility of the labels sliding out of the holder. Slidably mounted in a suitable guide 39 adjacent the lower end of the inclined table portion B' is a slide block 40 which is acted upon by a cam 41 mounted on the main drive shaft 14 for forcibly moving the block toward the label holder 32. Rigidly attached at one end to the rear wall of the label holder 32 is a telescoping push rod embodying rod sections 42 and 43. The outer rod section 42 which is attached to the holder 32 has a sliding bearing thru the guide 35 while the rod section 43 which telescopically fits into the rod sec-

tion 42 extends freely thru the guide 35' and has its end normally bearing against the rear face of the slide block 40. A combined return and take-up means is provided for the push rod for returning the label holder to its normal position and compensating for various forward degrees of movement of the holder, and this means includes an expansion coil spring 44 which acts between the guide 35 and a shoulder provided at the end of the rod section 42; and a second expansion coil spring 45 encircling the rod section 43 with one end acting upon the shoulder on the end of the rod section 42 and the opposite end of the spring acting upon an abutment formed by the enlarged end of the rod section 43. As the cam 41 rotates the springs 44 and 45 will be compressed and the label holder 32 moved into engagement with the paste coated end of the package whereby the front or outermost label will adhere to the paste and be withdrawn from the stack of labels. The springs will allow for complete rotation of the cam without any wedging action occurring and as the throw side of the cam 41 recedes from the slide block 40 the spring 44 and 45 will act to respectively withdraw the label holder and also return the rod section 43 into engagement with the slide block.

A novel advancing means is also embodied in the label gun for reducing the required throw of the cam 41 and also maintaining a substantially equal pressure on the pack of labels 33 at each throw of the gun as well as giving an even pressure on the labels when the holder is retracted, and also regardless of the quantity of labels in the holder. This means comprises a take-up rod embodying a pair of inner and outer telescopically related rod sections 46 and 47 respectively, arranged in parallel horizontal alignment above the telescopic push rod sections 42 and 43. The outer take-up rod section 47 slidably extends thru the rear wall of the label holder 32 and guide 35, and the inner end of the same is attached as by a spring 48 to the follower plate 36. The inner rod section 46 which has a sliding fit in the rod section 47 slidably extends thru the guide 35' and is normally held slightly spaced from the slide block 40 by a stop pin 49 engaging the rear face of the guide 35'. The spacing between the rod sections 46 and slide block 40 is slightly greater than the spacing between the open end of the label holder 32 and the end of the package to be labeled so that the label holder is moved into engagement with the end of the package prior to any movement imparted to the take-up rod. Take-up ratchet means 50 is provided in the advancing rod for maintaining an even pressure on the pack of labels as the labels are used up, and this means is shown in detail in Figure 7 wherein it will be seen that the rod section 46 is provided on its upper side with a series of ratchet teeth 51 engaged by a series

of spring pressed keepers or dogs 52 slidably supported to extend thru the upper side of the rod section 47. As will be observed in Figure 7 the spacing of the spring pressed keepers or dogs 52 is unequal to the length of the ratchet teeth 51 so that the keepers will alternately act to engage in the ratchet teeth upon very slight advance movement of the rod section 47 longitudinally away from the rod section 46. An expansion coil spring 53 acts to normally return the rod section 46 to its normal position in a manner as will be perfectly obvious from Figure 5. The spring 48 aside from relieving any undue shock or strain upon the keepers 52 also acts by reason of its being connected between the take-up rod and follower plate 36 as means for advancing the rod section 47 as the labels are used up by reason of the springs 37 exerting a forward pull on the rod section 47 thru their action upon the follower plate 36. As the slide block 40 is moved by the cam 41 the keepers 52 will cause the rod section 47 to be advanced against the follower plate 36 and thus firmly press the pack of labels against the paste coated end of the package.

Referring now to the label sealing means E for firmly affixing the labels to the packages, the same is shown in detail in Figure 6 and is mounted upon the inclined portion B' of the table B to the rear of the label gun D. The sealing means E includes a case 55 slidably mounted in a guide plate 56 provided with an upstanding guide 57. Slidably mounted in the case 55 is a presser plate 58 provided at its rear side with a marginal flange 59 which engages behind a sealing rim 60 shown in Figure 9 having a series of relatively small teeth 61 provided on its outer edge. The sealing rim 60 is removably held within the case 55 by suitable set screws 62 and as will be observed in Figure 9 the sealing rim permits outward movement of the presser plate 58. Secured to the rear wall of the case 55 are suitable leaf springs 63 which act upon the presser plate 58 for normally urging the same forwardly in the case 55. Rigidly affixed to the rear wall of the case 55 is a telescopic plunger rod embodying inner and outer rod sections 64 and 65 respectively, the rod section 65 having sliding movement thru the guide 57 and the rod section 64 being normally in contact with the rear side of the slide block 66 having sliding movement in a guide 67 mounted on the inclined table portion B'. The slide block 66 is engaged by a cam 68 mounted on the main drive shaft 14 whereby upon rotation of the cam the slide block is forcibly moved toward the guide 57. A combined relief and return means is provided for the seal operating plunger rod and consists of a pair of expansion coil springs 70 and 71 the former of which encircles the rod section 65 with one end acting upon the guide 57 and

its opposite end acting upon an abutment at the end of the rod section, and the latter of which encircles the rod section 64 with one end acting upon the end of the rod section 65 and the opposite end acting upon a shoulder provided on the rod section 64. Thus the springs 70 and 71 aside from returning the sealing case to its normal portion also act to relieve compression strain on the plunger rod when the case 55 is moved into engagement with the package by the cam 68.

As the seal is moved forwardly by the cam 68 the flat presser plate 58 firmly presses the label in position upon the package and the small teeth or projections 61 of the sealing rim 60 will firmly seal the edges of the label to the package by pressing the edges of the label into the package should the same be made of wood or similar relatively thick material. The modified form of sealing rim 60' shown in Figure 10 is for use when the labels are being applied to packages or receptacles made of thin pasteboard, tin or similar relatively thin material.

Pivotedly hung between the supporting rails 5 and 6 of the conveyor rack A adjacent the receiving conveyor J is a positioner 75 including a counter-balanced roller 76 which in its operative position engages the side of the package in the position designated P³ in Figure 1 for retaining the package P² and P³ in proper relative positions with respect to the label gun and sealing means. When the machine is fully loaded there are three packages as shown by dotted lines in Figure 1 held between the pivotally mounted rollers 24 and 76. A fourth package P⁴ in Figure 1 is resting on the slide 12 and in a position to be raised by the discharge transfer H to a position upon the receiving conveyor or rack J.

The revolving discharge transfer H includes a pair of parallel transfer arms 80 secured for rotation upon a horizontally disposed shaft 81 carrying a spiral gear 82 which meshes with a spiral gear 83 mounted on the main drive shaft 14. The arms 80 swing upwardly at opposite sides of the positioner 75 between the slides 12 and so engage beneath the package designated P⁴ as to elevate the package to a position upon the receiving conveyor J. The arms may be counterbalanced by a suitable weight 84. The roller 76 of the positioner 75 normally rests beneath the package in the position P⁴ and when the package P⁴ is elevated by the transfer H the roller 76 swings into position against the side of the package P³.

In operation of the machine, the packages fed along the conveyor G are raised by the transfer F upon the conveyor rack A and moved past the paste roll or disc 26 where a thin coating of paste is applied to one end of the package and the package then advanced to a position P¹ in Figure 1

and moving the previously transferred package to the position P^2 . The package in position P^2 is moved into the position P^3 . The cams 41 and 68 then actuate their respective mechanisms for applying a label to the package in position P^2 and sealing the label to the package in the position marked P^3 . As the packages are moved upon the slides 12 the transfer H removes the same to the receiving conveyor J where the packages may be led off to any desired point.

Having the packages moved thru the conveyor rack at an angle as shown will cause the ends to which the labels are to be applied at all times to be in engagement with the rollers of the front guide rail 9 and in a position to be properly engaged by the devices C, D and E regardless of any slight variations that may occur in the length of different packages.

From the foregoing description it will be apparent that a novel and improved construction for labeling machines has been disclosed wherein the packages or containers to have labels affixed thereto are automatically fed thru the machine and momentarily stopped at locations along the machine to be properly engaged by the label applying and sealing devices. It will also be observed that the packages are fed thru the machine at such an angular position as to insure movement of the packages by gravity into proper spaced relation to the label gun and sealing means. It will further be apparent that a novel type of label gun has been disclosed embodying an arrangement whereby a substantially equal pressure will be retained on the labels at all times regardless of the number of labels in the gun.

Changes in detail may be made to the form of invention herein shown and described, without departing from the spirit of the invention or the scope of the following claims.

I claim:

1. In a labeling machine, a conveyor rack, a revolving transfer for positioning packages in the feed end of the rack and causing limited movement of a group of packages along the conveyor rack, yieldable means engageable with opposite ends of the group of packages in the conveyor rack for preventing movement of the group in the rack, a discharge transfer for removing the packages from the discharge end of the rack, and means operating at one side of the rack for applying labels to the packages when at rest between the yieldable retaining means.

2. In a labeling machine, a conveyor rack, a transfer embodying revolving transfer arms for feeding packages to the forward end of the rack and causing movement of a group of the packages in abutting relation and with an intermittent movement along the rack, a yieldable keeper engageable with the foremost package of the group, label affixing means operating at one side of the rack for applying labels to the packages, a discharge transfer for removing the packages from the discharge end of the rack, and means operating at one side of the rack for applying labels to the packages when at rest between the yieldable retaining means.

fixing means operating at one side of the rack for applying labels to the packages, a discharge transfer for removing the packages from the rear end of the conveyor rack, and a yieldable positioner engageable with the rearmost package of the group and co-acting with the keeper for retaining certain of the packages in proper relation to the label affixing means.

3. A labeling machine including a conveyor rack, a feed conveyor extending transversely of the feed end of the conveyor rack, a revolving transfer including arms movable upwardly thru the feed conveyor for transferring packages therefrom to the conveyor rack, said conveyor arms causing movement of a group of packages in abutting relation and with an intermittent movement along the rack, labeling means for affixing labels to the packages, and a revolving discharge transfer for singly removing the labeled packages from the conveyor rack.

4. In a labeling machine, a conveyor rack including supporting rails each having a slide portion at its rear end, transfer means for causing movement of packages in abutting relation and with an intermittent movement along the rack, labeling means operating at one side of the rack for applying and sealing labels to the packages, said transfer means acting to cause movement of the labeled package upon the slides of the supporting rails, and a discharge transfer including revolving arms movable upwardly between the slides for transferring the labeled packages from the conveyor rack.

5. In a labeling machine, a conveyor rack, revolving feed and discharge transfers at opposite ends of the rack and alternately operable for respectively placing and removing packages on and from the rack, drive means for imparting corresponding rotation to the transfers, said feed transfer acting to move the packages with an intermittent movement along the rack and said discharge transfer acting to remove the foremost package during the interval while the packages are at rest on the rack, and labeling means operating at one side of the rack for applying and sealing labels to the packages.

6. In a labeling machine, a transversely inclined conveyor rack, transfer means for positioning packages on the rack, means for applying paste to the lower end of the packages while being positioned on the rack by the transfer means, means for applying labels to the paste coated ends of the packages, a discharge transfer for the labeled packages, and means for retaining the packages in position to be operated upon by the label applying means.

7. In a labeling machine, a transversely inclined conveyor rack, a paste roll rotatable at the lower side of the rack adjacent the feed end of the rack, a feed transfer for mov-

ing packages past the paste roll, a labeling gun operating at the lower side of the rack for applying labels to the paste coated surface of the packages, said feed transfer moving the packages in abutting relation and with an intermittent movement along the rack, means for sealing the labels to the packages, a discharge transfer for removing the labeled packages from the conveyor rack, and drive means for operating the label gun and sealing means when the packages are at rest in the conveyor rack.

8. A labeling machine including a transversely inclined conveyor rack, a revolving feed transfer for positioning packages on the conveyor rack, a discharge transfer for removing labeled packages from the conveyor rack, a single drive means for the feed and discharge transfers for rotating the same at like speeds, a paste applicator including a revolving paste roll for applying paste to one surface of the packages, a reciprocating label gun operating at the lower side of the conveyor rack for applying labels to the coated surface of the packages, and a reciprocating label sealer for pressing the labels firmly to the packages, said label gun and label sealer being operable by said drive means operating the feed and discharge transfers.

9. In a labeling machine, a conveyor rack, and a label gun for applying labels to one end of packages moved along the rack comprising a holder for receiving a pack of labels, a compressible push rod connected with the holder, means acting upon one end of the push rod for moving the holder into engagement with the package, and a second push rod slidable thru the holder and acting upon the labels for normally urging the labels forwardly in the holder.

10. In a labeling machine, a label gun including a reciprocating holder for containing a pack of labels, a compressible push rod connected at one end with the holder, a slide block engageable with the opposite end of the push rod for causing forward movement of the label holder, a follower plate in the holder at the rear of the labels, a telescopic take-up rod movable thru the holder and having one end yieldably coupled to the follower plate, and means for automatically causing the take-up rod to be extended as the labels are used from the holder, said take-up rod having longitudinal movement imparted thereto by said slide block subsequent to movement of the push rod for the holder.

11. In a labeling machine, a label gun comprising a holder, a guide plate for the holder including guide arms, a follower plate behind a pack of labels in the holder, spring means normally urging the plate and labels forwardly in the holder, a slide block, a push rod including telescopic sections one of which is attached to the label holder and slidable in one of the guide arms and the other of which

extends into engagement with the slide block, expansion springs encircling the rod sections for normally urging the label holder rearwardly and the rear rod section into engagement with the slide block, a take-up rod including inner and outer rod sections, said outer rod section having sliding movement thru the rear wall of the label holder at one of said guide arms and the inner rod section having sliding movement thru the companion guide arm, a spring yieldably connecting the forward end of the outer rod section with said follower plate, an expansion spring normally urging the inner rod section toward said slide block, means for retaining the inner rod section with its end spaced from the slide block, ratchet take-up means between the rod sections to permit automatic lengthening of the take-up rod, and cam means acting upon the slide block for imparting longitudinal movement to the push rod in advance of imparting longitudinal movement to the take-up rod.

12. In a labeling machine, a label gun including a label holder, a slide block, means for imparting sliding movement to the block, a compressible push rod between the holder and slide block for imparting sliding movement to the holder, and take-up means for maintaining a substantially equal pressure on the labels in the holder and normally urging the labels forwardly in the holder, including a telescopic take-up rod embodying rod sections, and ratchet means between the rod sections for allowing lengthening of the rod as the labels are used from the holder, said take-up means being actuated by said slide block.

13. In a labeling machine, a label gun for applying labels to containers as moved thru the machine, and means for sealing the labels upon the containers including a reciprocating case, a presser plate yieldable in the case, and a sealing rim encircling the pressure plate for engaging the marginal edges of the labels applied to the containers.

14. In a labeling machine provided with a label applying gun, means for sealing the labels to the packages comprising a sliding case, yieldable means for imparting longitudinal movement to the case, a presser plate in the case, spring means normally urging the presser plate forwardly in the case, and a sealing rim rigidly mounted in the case about the margin of the presser plate and having projections on its outer edge for biting into the marginal portions of the label engaged by the presser plate.
